(57) **CLAIM**

The ornamental design for a castle shaped dresser, as shown and described.

DESCRIPTION

FIG. 1 is a perspective view of my castle shaped dresser; FIG. 2 is a side elevation of one side of my castle shaped dresser shown in FIG. 1;

FIG. 3 is the opposite side elevation of my castle shaped dresser shown in FIG. 1;

FIG. 4 is a top plan view of my castle shaped dresser shown in FIG. 1;

FIG. 5 is a bottom plan view of castle shaped dresser shown in FIG. 1;

FIG. 6 is a rear view of my castle shaped dresser shown in FIG. 1; and,

FIG. 7 is a partial perspective view of my castle shaped dresser shown with an entry door shown in a lowered position.

The details shown in broken lines are for illustrative purposes only and form no part of the claimed design.
